BEVERAGE DISPENSER

Michael S. Lax, New York, N.Y., assignor to Kromex Corporation, Cleveland, Ohio, a corporation of Ohio

Application September 30, 1957, Serial No. 47,933

Term of patent 3½ years

(Cl. D44—26)

The dominant features of the dispenser are shown in solid lines.

I claim:

The ornamental design for a beverage dispenser, substantially as shown and described.
